EXPANSIBLE ABRASIVE WHEEL

John R. MacIntosh and Sam A. Mercurio, Chicago, Ill., assignors to Mermac Products, Inc., Chicago, Ill., a corporation of Illinois

Application August 6, 1957, Serial No. 676,602

16 Claims. (Cl. 51—191)

This invention is concerned with an expansible abrasive wheel, and more especially to a wheel of such character having a relatively rigid hub and a resilient, expansible rim mounted thereon.

An expansible wheel of the type herein considered, is disclosed in our copending patent application, Serial No. 560,981, filed January 24, 1956, now Patent No. 2,801,504, of which this is a continuation-in-part. In that application, the rim was noted as formed of rubber or similar resilient material having the characteristic of expanding under the influence of centrifugal force thereon when the wheel was rotated in excess of a predetermined velocity. Such expansion of the wheel to an enlarged diameter enabled an endless abrasive belt to be quickly and easily mounted upon the rim or to be removed therefrom; yet when the wheel was rotated, the abrasive band was frictionally gripped by the rim and held in place thereon.

The natural resilience of the material used in forming the rim was augmented by the inclusion of passages extending transversely therethrough and organized in spaced apart relation defining rows coaxial about the rotational axis of the wheel. These passages and the inherent resilience of the rim, provide a cushioning effect when an article to be abraded is pressed thereagainst, which we discovered to be exceptionally advantageous in that the continuous flexing of the belt kicked or propelled abraded particles therefrom and thus prevented glazing, and it permitted the grit or abrasive material of the belt to more effectively cut into a work material in contrast to impacting the same (which, if continuously repeated, caused the grit to chip off).

The passages, however, did not extend continuously across the rim, but instead terminated interiorly and alternately on opposite sides so as to give the wheel balance. It has now been found that the passages can be extended completely through the rim from side to side thereof, in contrast to the passages which terminated midway of the rim edges—provided that the passages are interrupted or otherwise constructed so as to prevent the unrestricted flow of air therethrough which causes a piercing whistle or noise when the wheel is rotated at its operational velocity. In accordance with this discovery, an object of the invention is to provide a rotatable wheel having passages extending transversely therethrough which do not create undesirable noise because of air flow in the passages.

Another object of the invention is to provide an expansible wheel structure having transversely extending passages therein that are designed so as to prevent or to so interfere with the air flow therein, that turbulence is created whereby undesirable noise developed by a continuous or uninterrupted air flow is substantially minimized. Still another object is that of providing an abrasive wheel having an expansible, resilient rim adapted to carry an abrasive belt circumjacent thereon, and which is provided with a plurality of passages oriented in arcuately spaced relation defining a circle about the rotational

2

axis of the hub—the passages having irregular or roughened surfaces, or having thin diaphragms or membranes therein to prevent a smooth flow of air through the passages when the wheel is rotated.

In use of an expansible abrasive wheel of the type described, it is found that there is a slight tendency for the endless abrasive belt to shift laterally at the time the wheel is gaining momentum and prior to the expansion to the full diameter thereof permitted by the band; and similarly, the same tendency toward lateral shifting is experienced when the velocity of the wheel is decreasing to zero. In certain instances during an actual abrading operation, the belt may tend to shift laterally to some degree if the belt and workpiece abraded thereby are engaged at an irregular angle—that is to say, at an angle such that a force component in the lateral or transverse direction is applied thereagainst as well as the usual force component normal thereto.

It has been discovered that this tendency of the belt to shift with respect to the expansible rim can be substantially negated by embossing the circumferential surface of the rim in a manner such that the belt has a greater tendency to cling thereto, and the provision of a wheel having this advantage is a further object of this invention. Yet another object is to equip the circumferential surface of an expansible abrasive wheel adapted to have an endless abrasive belt mounted thereon, with a design configuration comprising a plurality of recesses which cooperate with and are implemented by the flexing or yielding of the expansible wheel as described hereinbefore, to draw the belt tightly against the surface of the wheel and thus minimize its tendency for lateral shifting.

Still a further object is to equip the expansible rim of an abrasive wheel with a plurality of depressions or recesses, that may be a plurality of separated recesses of minute diameter or serpentine grooves of minute width, which suck the belt toward the surface of the rim because of a slight vacuum that develops as the normal air within such recesses is expelled during flexing of the belt and underlying rim. Additional objects and advantages of the invention will become apparent as the specification develops.

Embodiments of the invention are illustrated in the accompanying drawing, in which

Figure 1 is an end view in elevation of an expansible abrasive wheel embodying the invention, and in which an endless abrasive belt mounted upon the wheel is broken away to show the wheel surface; Figure 2 is a side view in elevation of the wheel illustrated in Figure 1, but with the endless abrasive belt removed; Figure 3 is a broken vertical sectional view taken along the line 3—3 of Figure 2; Figure 4 is an end view in elevation of a modified abrasive wheel structure; and Figure 5 is a broken vertical sectional view similar to that of Figure 3, but being taken through the modified wheel structure of Figure 4.

The expansible abrasive wheel structure illustrated in Figures 1 through 3 is designated in its entirety with the numeral 10, and is seen to comprise a relatively rigid hub 11 having a central bore 12 extending therethrough adapted to receive a rotatably driven shaft so as to be rotated about the longitudinal axis thereof. The hub can be secured to such shaft so as to be driven thereby in any suitable manner as, for example, by clamp collars, lock nuts, etc. The wheel comprises also an expansible, resilient rim 13 that, as shown in Figure 1, is adapted to have an endless abrasive belt or band 14 mounted in circumjacent relation thereon.

The band 14 has substantially the same width as that of the rim 13, and the inner diameter thereof is slightly greater than the outer diameter of the rim when the wheel is at rest; but when the wheel is rotated, cen-

trifugal force causes the rim to expand into tight frictional engagement with the belt 14 so as to firmly anchor the belt thereon. As has been brought out hereinbefore, there are in certain instances a tendency for the belt 14 to shift laterally with respect to the rim 13, and we have found that this tendency can be substantially obviated by equipping the circumferential surface of the rim with a plurality of recesses or depressions therein which, as shown in Figure 1, are in the form of substantially identical grooves or channels 15 arranged in spaced, side-by-side relation.

The precise number of grooves 15 will depend upon the width of the rim 13 and, for example, with a wheel having a rim width of about one inch, there may be 20 such grooves. Preferably, the grooves extend completely about the circumference of the rim, although interruptions therein are permissible. The grooves are quite shallow, and in the example set forth may have a depth of about $\frac{1}{32}$ of an inch. It is most desirable that the grooves have an irregular or serpentine configuration, as shown in Figure 1, for this will prevent scouring or marring of the work material abraded by the wheel as could be experienced if the grooves were straight.

In further accordance with the example, the maximum total amplitude of the generally sinusoidal wave pattern (a complete cycle) illustrated in the specific embodiment of Figure 1, and which is designated as the dimension A in that figure, may be about one-eighth of an inch. The dimension B represents the entire curve length (that is, a complete sinusoidal cycle); and should have a length of about one and one-half inches. It should be understood that the specific figures are set forth solely as examples, and the dimensions represented thereby could be varied sharply.

The modified wheel structure illustrated in Figures 4 and 5 is denoted with the numeral 16, and may be structurally similar to the wheel 10 heretofore described. It will be noted in Figure 4 that the depressions or recesses take the form of small individual pocks or dents 17 oriented into transversely extending rows 18 and circumferentially extending rows 19. In the specific illustration, there are three such circumferential rows 19, and the transverse rows 18 may be spaced apart about one-eighth of an inch. Each of the recesses 17 may have a diameter of about $\frac{1}{16}$ of an inch, and a depth of about 0.020 inch. It will be understood that considerable dimensional variation may be incorporated in the design shown in Figure 4, and the number of rows 19 is in no sense fixed. Also, while the rows 19 are straight, they could be arranged in other configurations such as the serpentine configuration shown in Figure 1.

Returning to the wheel structure 10 shown in Figures 1 through 3, it will be noted that the rim 13 thereof is provided with a plurality of passages 20 and 21 extending transversely thereof. The passages 20 are oriented in spaced apart relation, and define an inner circular row designated generally with the numeral 22 having its center at the center or rotational axis of the hub. The outer passages 21 are also positioned in spaced apart relation, and define an outer row denoted generally with 23 which is concentric with the row 22. The passages 20 of the inner row and 21 of the outer row are offset angularly with respect to each other, and define an alternate or staggered interrelation.

Referring to Figure 3, it will be seen that each of the passages 20 and 21 is interrupted intermediate the ends thereof with a thin membrane 24 and 25 respectively, which may or may not be imperforate. These membranes may be located at any convenient position intermediate the ends of the passages, and in the specific illustration are adjacent an end portion thereof. The structure shown has the membranes 25 of the passages 21 located adjacent one side of the rim 13, while the membranes 24 are adjacent the opposite side of the rim.

In the modified wheel structure of Figure 5, inner and outer transverse passages are also incorporated in the rim 26 thereof, and are designated with the numerals 27 and 28. Such passages may be identical to the passages 20 and 21 with respect to the locations and arrangement thereof, but it will be noted, do not have a membrane interrupting the continuity thereof. Rather, the surfaces defining the interior of the passages are irregular, and such irregularity may be provided in any suitable manner as, for example, by piercing the rim to form the passages therein.

The passages through the rims of the respective wheels 10 and 16 are shown in generally rectangular form, and each has a slight curvature corresponding to the circular arc on which they lie. However, the passages may have other configurations, and may be round, or teardrop configuration, etc.

In use of the structures described, the respective abrasive wheels are mounted upon a shaft and are rotatably driven thereby. The endless abrasive belt 14 which is initially loose on the wheel, is tightly gripped as the rim expands and the assembly is then in readiness for an abrading operation. The transversely extending passages serve the function of softening the expandible rim in its entirety without decreasing the unit firmness thereof, and together with the natural resilience of the rims serve as a cushion whereby the rim is depressed at the point of engagement thereof with a workpiece. As soon as any such depressed point is rotated beyond the workpiece, it springs outwardly and to its normal position. Thus, a constant or repetitive flexing occurs at each point along the rim as the wheel is rotated in an abrading operation.

This flexing has the advantage of expelling abraded particles from the belt 14, thereby keeping it clean with the result that it does not glaze, and with the further result that the abrasive grit does not chip whereupon the belt has relatively long life and cuts more effectively and rapidly. The flexing of the wheel also serves to move air through the transverse passages, and the flow of air therethrough carries away heat and tends to keep the rim relatively cool. It has been found that when the passages have a configuration that interrupts or disturbs the flow of air therethrough, the wheel does not whistle or otherwise develop objectionable noises during use. The membranes 24 and 25 serve to so interrupt the flow of air through the passages, and the irregular configuration of the surfaces of the passages 27 and 28 also achieves a sound eliminating result by disturbing the air flow through the passages. Apparently, the roughened or irregular surfaces are sufficient to create turbulence of the air and thereby prevent a smooth flow which, it is believed, is the cause of the objectionable noise.

The recesses in the circumferential surface of the expandable rims, which are in the form of shallow grooves 15 in Figure 1 and individual recesses of diminutive size in Figure 4, tend to more firmly affix the belt 14 in its circumjacent relation upon the rims and thereby minimize the tendency for lateral displacement thereof during starting and stopping of the wheel, and during abrading operations wherein laterally oriented forces are applied against the belt. It appears that this holding action is provided because of the flexing of the rim, and consequently a result of the inclusion of the transversely extending passages. It is believed that the flexing of the rim expels air from the grooves 15 and recesses 17 so that a slight vacuum develops therein. This vacuum or negative force in being applied to the belt 14, causes it to adhere even more tightly to the rim. Moreover, the edges of the recesses as a result of such suction, tend to bite into the belt and thereby increase the frictional resistance to movement thereof.

While in the foregoing specification embodiments of the invention have been set forth in considerable length

and detail, it will be apparent to those skilled in the art that variations in those details may be made without departing from the principles and spirit of the invention.

We claim:

1. In an expandable abrasive wheel structure, an expandable, resilient rim adapted to be rotatably driven, said rim being diametrically dimensioned so as to receive an endless abrasive belt thereon when the rim is at rest but to expand into gripping engagement with such belt when the rim is rotated at a predetermined velocity, said rim being provided with a plurality of shallow recesses about the circumferential surface thereof to resist lateral shifting of such belt thereon, said rim having a plurality of passages extending transversely thereof provided with means for disturbing the movement of air therein to minimize sound which would otherwise be created by the movement of air therein.

2. The wheel structure of claim 1 in which said recesses comprise a plurality of circumferentially extending grooves.

3. The wheel structure of claim 2 in which said grooves have an elongated curvature along the length thereof to define a departure from a straight circumferential line.

4. The wheel structure of claim 1 in which said recesses comprise minute depressions located throughout the circumferential surface of said rim.

5. The wheel structure of claim 4 in which said depressions are oriented in a plurality of circumferentially and transversely extending rows.

6. In a wheel structure of the character described, a wheel adapted to be rotatably driven, said wheel being provided with a plurality of passages extending transversely therethrough, and means for disturbing the flow of air through said passages when said wheel is rotated to substantially minimize sound which would otherwise be created by the flow of air therethrough.

7. The wheel structure of claim 6 in which each of said passages is provided with a membrane intermediate the ends thereof to effectuate such disturbance of the air flow therethrough.

8. The wheel structure of claim 6 in which said passages have irregular walls defining the same to provide such disturbance of the air flow therethrough.

9. In an abrasive wheel structure of the character described, a resilient, expandable rim adapted to be rotatably driven, said rim being dimensioned to slidably receive an endless abrasive belt thereover when the rim is at rest and to expand into tight resilient engagement with such belt when the rim is rotated, said rim being provided with a plurality of passages extending transversely therethrough, and air flow disruption means within said passages for interfering with the flow of air therethrough.

10. In an abrasive wheel structure of the character described, a resilient, expandable rim adapted to be rotatably driven, said rim being dimensioned to slidably receive an endless abrasive belt thereover when the rim is at rest and to expand into tight resilient engagement with such belt when the rim is rotated, said rim being provided with a plurality of passages extending transversely therethrough, and air flow disruption means within said passages for interfering with the flow of air therethrough, said rim being provided with a plurality of recesses along the circumferential surface thereof operative to resist lateral movement of such a belt positioned thereon.

11. The wheel structure of claim 10 in which said passages are oriented in spaced apart relation adjacent the circumferential surface of said rim and aligned in a row defining a circle concentric therewith, and in which said recesses are relatively shallow.

12. The wheel structure of claim 11 in which said disruption means comprise projections extending interiorly into said passages, and in which said recesses are aligned in circumferentially extending orientation.

13. In a structure of the character described, a wheel adapted to be rotatably driven and comprising a relatively rigid hub having a centrifugally expandable rim anchored thereon diametrically dimensioned so as to slidably receive an endless abrasive belt when the rim is at rest but to expand into gripping engagement with such belt when the rim is rotated at a rate in excess of a predetermined velocity, said rim being provided with a plurality of passages extending transversely thereof equipped with means for disturbing the flow of air therein when said wheel is rotated to substantially minimize the sound which would otherwise be created by the movement of air therein.

14. The structure of claim 13 in which said rim is provided along the circumferential surface thereof with a plurality of relatively shallow recesses effective to resist lateral shifting of such a belt positioned thereon.

15. The structure of claim 14 in which said recesses extend along the circumferential surface of said rim.

16. The structure of claim 14 in which said recesses comprise a plurality of relatively small depressions oriented in spaced relation along the circumferential surface of said rim.
